UNITED STATES PATENT OFFICE.

FREDERICK H. HAWKINS, OF NEW YORK, N. Y.

MACHINE FOR EMBOSSED ORNAMENTAL DESIGNS ON WOOD OR OTHER MATERIAL.

SPECIFICATION forming part of Letters Patent No. 448,486, dated March 17, 1891.

Application filed May 13, 1890. Serial No. 351,703. (No model.)

To all whom it may concern:

Be it known that I, FREDERICK H. HAWKINS, a subject of the Queen of Great Britain, residing at 550 East One hundred and forty-third street, city of New York, and county and State of New York, have invented certain new and useful Improvements in Machines to Emboss Ornamental Designs or Irregular-Shaped Articles of Wood or other Material, 10 of which the following is a specification.

Heretofore in machines constructed for the purpose of ornamenting wood or other compressible material by means of passing the same between rotating dies and feed-rollers, no provision has been made whereby any article 15 of an irregular shape, such as brackets, can be ornamented. By this invention articles of irregular shape can be ornamented with designs similar to straight work. I attain the 20 object of this invention by means of the mechanism shown in the accompanying drawings, in which—

Figure 1 is a side view of the machine. Fig. 2 is a front view of the machine; Fig. 3, a 25 view of the bed of the machine, also showing the die; and Fig. 4 is a view showing the method of passing a bracket or other article under the die. Fig. 5 is a cross-section of the feed-roller and sliding bed on the line a 30 b, Fig. 4.

Similar letters refer to similar parts throughout the several views.

The bracket *a* or other article to be embossed is fastened to a sliding bed *b* by means 35 of the clamps *c* and *c'*. A bed-piece *c*² is placed under the bracket, so as to bring it to the best position for embossing. On the under side of the sliding bed *b* is two racks *b'* *b'*, which engage with the gear-wheels *d* and 40 *d'*, which form part of the feed-roller *d*². This sliding bed *b* is provided on its upper side near its longitudinal edges with guard-flanges *m*, which are designed to receive the outer ends of the engraving-die to regulate its 45 pressure upon the stock to be ornamented. The die *e* is fastened to a revolving shaft *e'* at the free end of the arm *g*, the arm *g* being connected at *g'* to a suitable standard *g*². The free end of the arm *g* has a vertical motion, so as to adapt it to various shapes and 50 sizes of work, and is connected to the wheels *h* *h'* by means of the arms *h*' *h*'. These wheels

are fastened to the shaft *h*². At the end of the shaft *h*² is fastened an arm *h*³, and by means of the tension-rod *k*, the lever *k'*, and weight *k*² a yielding pressure is brought to bear on the die, so that the article is ornamented as it is passed under the die. At each side of the sliding bed *b* are two guides *m m*. These can be made of different sizes, 60 so as to suit the article to be embossed. At the rear side of the machine a suitable train of gear-wheels is attached to actuate the bed and the dies. A standard *n*, arm *n'*, and hanging arm *n*² serve to guide and carry the 65 parts actuating the arm *g* in suitable bearings *o o*. Connected to the standard *n* and hanging arm *n*² is fastened a rotating shaft *o'*, having pinions *o*², meshing into the gearing formed on the edge of the wheels *h* *h*. 70 At one end of the shaft *o'* is fastened the hand-wheel *o*³. The object of this hand-wheel is to raise the free end of the arm *g*, as may be desired.

The gearing to operate the dies, &c., consists of the driving-pulleys *p p p* and the pinion *p'*, connected to the shaft *p*² by means of the intermediate gear-wheels *s s' s*². The die and feed-rolls are actuated by means of the gear-wheels *s*³ and *s*⁴. In many cases better results can be obtained if the feed-roller and the die are not geared to work together, in which case either of the intermediate gear-wheels can be removed.

To operate the machine the die is first fixed 85 to the shaft so as to bring the pattern to the right place on the article to be ornamented. The article is then fixed in place on the bed *b* and the guides *m m* placed on each side, (if required.) The machine being now set in 90 motion, the bed *b* carries the article under the revolving die. The guides *m m* first coming in contact with the face of the die near the ends raise the die sufficiently to allow that part of the article that is not to be ornamented to 95 pass clear of the die, all other parts being embossed as the die is forced into the article by means of the mechanism connected to the lever *k'* and weight *k*². The article can be passed back and forth under the die till the 100 desired effect is obtained. In all articles that require elaborate ornamentation they should be fastened to the sliding bed *b* and passed several times back and forth under the die.

By this means more perfect work can be obtained. When the machine is used on simple straight work, the sliding bed *b* can be removed and the machine used in the usual way. The base or stand of the machine can be made as shown or in any other suitable form.

What I claim as my invention, and desire to secure by Letters Patent, is—

- 10 1. A sliding or movable frame adapted to support stock, having vertical guards, in combination with a vertically-movable engraving-die limited in its downward movements by said guards, substantially as specified.
- 15 2. In a machine for ornamenting wood and other material, the combination, with a sliding frame having teeth on its under side and vertically-disposed guards on its upper side, of a vertically-yielding engraving-roll limited 20 in its downward movement by said guard, and one or more pinions on a shaft for moving the rack and its frame, substantially as specified.
- 25 3. The combination, with the main frame, of the rack-frame having vertically-disposed guards on its upper side, the clamps also on the upper side, the angular piece arranged between the clamps, the feed-roller below the movable frame, the pinions on the shaft of 30 said roller for moving the rack and its frame, and suitable means for rotating said shaft, substantially as specified.
- 35 4. A machine for ornamenting wood and other material, having a vertically-adjustable engraving-die rotated by gearing, a movable stock-table also operated by gearing and having vertical guard-flanges, an inclined bearing-block on its face, clamps for confining stock on said bearing-block, tension devices 40 connected with the movable engraving-die to hold the same depressed, and mechanical means for simultaneously raising the engrav-

ing-die and relieving the tension devices from said die, substantially as specified.

5. The combination, with the main frame, 45 of the standard rising therefrom and having the horizontal branch and also the hanger formed thereon, a shaft journaled in said standard and carrying one or more gear-wheels, a horizontal shaft having a pinion engaging said gears, a hand-wheel on the pinion-shaft, a vertically-movable engraving-die, arms connecting the die with said gears, an arm fixed to one end of the gear-shaft, a weighted lever pivoted to the main frame, and 55 an arm connecting the arm of the weighted lever with the arm secured to said gear-shaft, substantially as specified.

6. A machine for ornamenting wood and other material, having a movable stock frame 60 or table, an angular bed-piece secured thereto, a vertically-movable engraving-die, gearing for rotating the die, gearing for raising and lowering said die, and a tension device connected with the latter-named gearing, substantially as specified.

7. In a machine for ornamenting wood, the base or stand, the standard *n*, arm *n'*, and hanging arm *n''*, in combination with the swinging arm *g*, the die *e*, the pressure device 70 consisting of the arms *h' h'*, the wheels *h h*, the shaft *h''*, the arm *h''*, the tension-rod *k*, the lever *k'*, and weight *k''*, also the hand-wheel *o''*, the shaft *o'*, pinions *o''*, and wheels *h h* to lift the free end of the swinging arm *g*, the 75 driving mechanism consisting of the pulleys *p p p*, the gear-wheels *p' s s' s'' s'' s''*, the feed-roller *d''*, and pinions *d* and *d'*, all substantially as shown, and for the purpose specified.

FREDERICK H. HAWKINS.
